UNITED STATES PATENT OFFICE.

HIRAM PIERCE, OF CLAREMONT, NEW HAMPSHIRE.

MACHINE FOR STRAIGHTENING KNIFE-BLADES.

Specification of Letters Patent No. 17,634, dated June 23, 1857.

To all whom it may concern:

Be it known that I, HIRAM PIERCE, of Claremont, in the county of Sullivan and State of New Hampshire, have invented 5 certain new and useful Improvements in Machinery for Straightening Knife-Blades; and I do hereby declare the following to be a full, clear, and exact description of the same, reference being had to the accompanying drawing and to letters of reference marked thereon.

My invention relates to improvements in the dies usually employed, in conjunction with a drop weight, for straightening knife 15 blades, and consists in so arranging the upper or lower die, or both, as to be self-adjusting, thereby allowing the faces of the two dies to accommodate themselves to the tapering form of the blades.

20 My invention has for its aim the straightening of blades and imparting to their bolsters and tangs, their proper form and position, and this without the necessity of submitting the blades to more than one heat.

25 In order to enable others skilled in the art to make and use my invention, I will now proceed to describe its construction and operation.

On reference to the drawing which forms 30 a part of this specification, Figure 1 is a front elevation of a machine for straightening knife blades with my improvements on the same. Fig. 2, an edge view; Figs. 3 and 4 sectional views drawn to an enlarged 35 scale and illustrating the mode of rendering the upper die self adjusting.

Similar letters refer to similar parts throughout the several views.

A is the base of the machine to which are 40 secured the two guides or pillars B and B' connected together at the top by the cross-bar C.

D is a drop weight guided by the pillars B and B' and suspended to a band E which 45 is attached to and arranged to be wrapped around the pulley F, the latter being loose on the shaft G which turns in boxes a, a, secured to the pillars. On the same shaft G is a clutch having projections adapted to 50 recesses in the face of the pulley F. This clutch is arranged to slide freely on the shaft but not to turn independently of the same.

I is a bell crank lever turning a pin 55 attached to the column B, the bent arm of the lever terminating in a projection which

fits between the collars on the clutch H and the straight arm of the lever being connected to the rod J which is arranged to slide in guides attached to the pillar B'. 60 On the rod J are secured an upper catch b, and lower catch c, both being so situated as to be struck by a bar d, attached to and projecting from the drop weight D.

K is a spring treadle jointed to the base 65 A and connected by means of a rod L to the lever M which passes through the pillar B, and has its fulcrum on a pin attached to the same, the point of the lever projecting a short distance from the inside of the 70 pillar.

N is a crosshead, secured to the two pillars and in this crosshead slides the rod O which is furnished at the top with a collar e, and between the latter and the top 75 of the cross-head intervening a spiral spring f. The rod O is furnished with another collar h below which it terminates in the spherical end g one-half of the latter, fitting into a hemispherical recess in the 80 plate i, in which position it is retained by the upper plate j. To the plate i is secured the upper die P and to the base plate another die Q both dies having steel faces, 85 adapted to the blades to be straightened, and having suitable recesses k for the bolster d of the blade R. The pins r attached to the lower die, serve as guides for the upper die. A strap from any adjacent shaft being applied to a pulley S on 90 the shaft G so that the latter may revolve in the direction of the arrow, the band E is wound around the pulley F, with which the clutch H is now in gear, and consequently the weight D is elevated until the projection 95 d strikes the catch b when the rod J is raised and the bell crank lever I so moved as to throw the clutch H out of gear from the pulley I when the latter can turn freely on the shaft G and the weight D may fall, 100 it is however retained by the point of the lever M until the attendant presses down the spring treadle, when the weight is released, and falling strikes the top of the rod O thereby submitting the heated blade 105 R to the percussion imparted to the upper die. Simultaneously with the dropping of the weight, the projection d struck the inclined catch on the rod J, the descent of which had moved the lever I so as to throw 110 the clutch H in gear with the pulley F, consequently as the shaft continues to re-

volve the weight will be raised as before, preparatory to being again caused to fall by operating the treadle. As the weight is raised from contact with the rod *O* the 5 spiral spring elevates the said rod and with it the upper die to a height limited by the collar *h*. The heated blade *R* is submitted to a series of such percussions until it becomes perfectly straight, and until its 10 bolster and tang assume the required form and position. In thus rendering the upper die adjustable by means of the spherical end of the rod *O*, the above object is attained without constantly re-heating the blade 15 which has hitherto been a matter of necessity and consequent cause of delay in former contrivances used for effecting the same purpose.

I do not desire to claim the devices for 20 raising and dropping the weight, and I do

not wish to confine myself to the rendering of the upper die only, adjustable, as that may be permanent and the lower die self-accommodating to the tapering form of the blade, or both dies may be made adjustable. 25 But

What I claim and desire to secure by Letters Patent is:

The employment in conjunction with a drop weight of self adjusting dies in the 30 manner, and for the purpose herein set forth.

In testimony whereof, I have signed my name to this specification before two subscribing witnesses.

HIRAM PIERCE.

Witnesses:

CHAS. BARDWELL,
OTIS F. R. WAITE.
